[57] CLAIM

The ornamental design for a combined blood collection and analysis instrument, as shown and described.

DESCRIPTION

FIG. 1 is a perspective view of a combined blood collection and analysis instrument showing our new design;

FIG. 2 is a top plan view thereof;

FIG. 3 is a front elevational view thereof;

FIG. 4 is a right side elevational view, the left side elevational view being a mirror image;

FIG. 5 is a left side elevational view thereof;

FIG. 6 is a rear elevational view thereof; and,

FIG. 7 is a bottom plan view thereof.

The broken line showing of the power cords in the FIGS. 2 and 4 through 7 are for illustrated purposes only and forms no part of the claimed design.
